UNITED STATES PATENT OFFICE.

BENJAMIN T. BROOKS, OF BAYSIDE, NEW YORK, ASSIGNOR, BY MESNE ASSIGNMENTS, TO CARBIDE AND CARBON CHEMICALS CORPORATION, A CORPORATION OF NEW YORK.

PROCESS OF MAKING MOTOR SPIRITS AND REFINING PETROLEUM PRODUCTS.

No Drawing.

Application filed May 1, 1918. Serial No. 231,802.

To all whom it may concern:

Be it known that I, BENJAMIN T. BROOKS, a citizen of the United States, residing at Bayside, county of Queens, and State of New York, have invented certain new and useful Improvements in Processes of Making Motor Spirits and Refining Petroleum Products, fully described and represented in the following specification.

10 This invention relates to a process of making motor spirit, and of refining petroleum products.

In carrying out this process, the starting material is a petroleum product, as, for example, either crude petroleum, or the distillates or residues obtained from crude petroleum. In practice, the petroleum product known as gas oil, is particularly applicable, because it consists chiefly of high boiling 15 hydrocarbons of the aliphatic series, which are especially suitable for carrying out the present process and, furthermore, it is a cheap starting material at the present time.

20 The starting material is cracked under such conditions as to give a resultant liquid product rich in hydrocarbons of the olefin series.

In the cracking processes hitherto employed for the production of motor spirit, 25 it has been customary either to crack the oil at relatively low temperatures; for example, below 600° C., or to perform the cracking operation under relatively high pressures; that is to say, at pressure of two atmospheres or above. The purpose of maintaining the low temperatures, when cracking at atmospheric pressures or thereabouts or of employing the high pressures, has been to avoid as much as possible the production of 30 unsaturated hydrocarbons such as olefins in the product. The production of some olefins has been considered unavoidable but generally efforts were made to reduce the proportion of such bodies to a minimum.

35 While some attempts have heretofore been made to utilize as motor spirit certain low boiling petroleum products containing considerable olefins, these attempts have not been satisfactory.

40 The present applicant has found that the difficulties have been due to the fact that in the production of such motor spirit not only olefins, but also diolefins and certain malodorous substances, such as pyridine bases,

sulphur compounds and naphthenic acids, 55 exist in the final product.

By the present invention a petroleum product is used as a starting material and is subjected to a cracking process under conditions such as to give a good percentage of 60 low boiling olefins, liquid at normal temperatures. The conditions of cracking which will give this result are well known, but have generally been avoided heretofore in the manufacture of motor spirit. Under 65 such cracking process, the low boiling constituents comprise saturated hydrocarbons and also olefins. Sometimes there may be aromatic hydrocarbons present, but these need not be specially considered at the present time as they are an advantage in the final product and are not affected by the refining process comprising an essential feature of 70 the present invention.

The olefins in the cracked product will 75 comprise some diolefins. These are not only of no advantage, but are a positive disadvantage, because of their carbonizing effect in the engine cylinder and the troubles 80 which they cause in the carburetor, i. e., the formation of a sticky, resinous compound.

The present process results in producing a motor spirit substantially free from such diolefins.

To obtain the greatest advantages of the 85 present invention, it is important to crack the petroleum product under conditions which will give an olefin-rich cracked product and then distil the same in the usual way to obtain the low boiling fractions.

90 At the same time, it is to be understood that the invention is not limited to any particular cracked product, since the refining steps hereinafter described are applicable to any petroleum product.

95 In carrying out the present process, the product of the cracking process is mixed with 5 per cent by volume of an aqueous solution of sulfuric acid of Baumé gravity materially less than 60°, containing for example about 75 to 80 per cent H_2SO_4 , and then thoroughly agitated for about half an hour, at ordinary temperature. The mixture is then allowed to stand until it stratifies. It will be found that layers of acid and of tar form at the bottom. The acid and tar are then drawn off. The oil remaining 100 is then washed with alkali in the usual way.

After this, the oil is re-distilled, only a small amount of tails of a heavy product being left behind. In this re-distillation, the distillate is collected as one product—that is to say, there is no fractionating.

The distillate is a clear product forming an excellent motor spirit having no unpleasant odor and not deteriorating either by decomposition or otherwise when kept 10 for a considerable time.

When used as motor spirit it volatilizes satisfactorily in the usual carburetors such as are employed for the so-called commercial 15 gasolines now in general use and the power output by volume is excellent.

This product contains paraffins and olefins, but seems to be substantially free from diolefins or derivatives thereof, and from hydrocarbons of the acetylene series.

20 Instead of carrying out the process as described above, it may be modified while still attaining the desired result. For example, instead of treating the product of a petroleum cracking process with sulfuric acid in an unconcentrated condition, it may be treated with ground niter cake or sodium acid sulfate or other acid sulfate, or a mixture of such acid sulfates. The other steps 25 of the process may be the same as before.

30 Furthermore, instead of washing the product with an alkali wash, it may be treated with soda-lime. Great advantage in the purifying of such products results from the use of soda-lime, due in part to the physical 35 properties of the soda-lime.

In subjecting the petroleum product to the treatment with soda-lime, several methods may be employed. For example, the 40 soda-lime and hydrocarbon material may be mixed and agitated, then allowed to settle and the purified product drawn off. Or the hydrocarbon material may be percolated through a layer of soda-lime. Further, the soda-lime may be used in the still when re-distilling the product. In carrying out this 45 treatment, the soda-lime may be placed either in the body of the oil in the still, or it may be placed as a body or layer in the path of the vapors evolved by the still, so that 50 said vapors must traverse the body or layer of soda-lime.

The soda-lime, owing to its porosity and capability of retaining its shape, forms an admirable material for the passage of the 55 hydrocarbon liquid or vapor through its mass.

By using a relatively dilute or non-con-

centrated sulfuric acid as specified above, in refining a product containing acetylenes or diolefins, very important results are attained 60 as compared with the use of concentrated sulfuric acid. For example, when concentrated acid is used the loss of product to the acid is large, much tar is dissolved in the acid making the acid recovery difficult, 65 sulpho-acids are formed in relatively large amounts and the mono-olefins are attacked, being in part dissolved and in part polymerized to form oils and tars.

On re-distilling such a product treated 70 with concentrated sulfuric acid, a yellow distillate is obtained and much SO_2 is given off. Also the high boiling residue is large. By the present process, when the sulfuric acid is dilute, the loss to acid is small, tars 75 are only partly dissolved by the acid, the sulpho-acids are formed only to a slight extent, mono-olefins are practically unaffected, and on re-distillation of this product there is little SO_2 and the distillate is white. Diolefins are resinified and thus removed while all malodorous nitrogen bases are removed. The subsequent recovery or regeneration of 80 the sulphuric acid is more efficient since it contains less dissolved organic matter, in the 85 presence of which the sulphuric acid is decomposed to SO_2 and water, and certain oxidized products of the organic matter are formed.

What is claimed is:

1. The process of making motor spirit which comprises cracking a petroleum product under conditions giving a material rich in olefins, subjecting this material to the action of a sulphuric acid equivalent to 90 strong aqueous H_2SO_4 of Baumé gravity materially less than 66° , separating the oil from the substances immiscible therewith, treating the separated oil with an alkali, and distilling off and collecting the oil. 100

2. The process of treating distillates produced by the cracking of petroleum oils which comprises subjecting said distillates to the action of a sulphuric acid equivalent to strong aqueous H_2SO_4 of a Baumé 105 gravity materially less than 66° , separating said distillates from the substances immiscible therewith, treating the said separated distillates with an alkali and distilling off and collecting said distillates. 110

In testimony whereof, I have hereunto set my hand.

BENJAMIN T. BROOKS.
